UNITED STATES PATENT OFFICE.

RICHARD E. HORNBECK, OF RICHMOND, CALIFORNIA.

SHIP AND BOAT CONSTRUCTION.

1,266,469.

Specification of Letters Patent. Patented May 14, 1918.

Application filed June 4, 1917. Serial No. 172,819.

To all whom it may concern:

Be it known that I, RICHARD E. HORNBECK, a citizen of the United States, and resident of Richmond, California, have invented certain new and useful Improvements in Ship and Boat Construction, of which the following is a specification containing a full, clear, and exact description, reference being had to the accompanying drawings, forming a part hereof.

My invention relates to an improved art of constructing and operating ships and boats, and it consists in the novel subject-matter which is hereinafter particularly described and distinctly claimed.

The principal object of my invention is to make ships and boats with a plurality of separate hulls having a fin fixed between the two adjacent hulls, and said fin provided at one or both of its ends with a hinged apron or rudder which may be inclined at will upwardly or downwardly, to cause the hulls to rise or sink as the hulls move forward or back in the water, whereby the boats or ships thus constructed will be made safer and speedier, and be enabled to carry an increased net tonnage, the construction and mode of operation being such that should either of said hulls from any cause spring a leak the remaining hull (or hulls) would continue to hold the leaking hull up, and thus eliminate many ship and boat founders.

A further object of my invention is to construct and operate ships and boats in such an improved manner that all ballast and other weights (which are essential in the boats and ships heretofore known to me) will be eliminated, as unnecessary; and yet the improved ships and boats, made and operated in accordance with my invention, will be held steady, and be kept from founders, and undue rocking in the water; whereby a large amount of gross tonnage will be eliminated, and the net tonnage will be correspondingly increased in thus increasing the net tonnage capacity.

A further object of my invention is to construct and operate ships and boats with a plurality of hulls with movable aprons between them, in such a manner that said aprons (or fins), or a portion thereof, may be inclined upwardly by the operator, sufficiently to raise the ship or boat nearer the surface of the water, as the vessel is propelled forward or backward, and thereby

cause less water resistance, depending upon the speed of the vessel and the angle of inclination of said aprons, the water resistance being reduced gradually more and more as the speed is increased, and permitting the speed to be increased with economy of the propelling power.

A further object of my invention is to construct improved vessels, which, while at sea during a storm, and being provided with my invention, may lower the front edge of the apron or fin, and thus cause the vessel to be more or less submerged, as desired, to remove all or a large part of the vessel from exposure to the action of the storm.

A further object of my invention is to provide plural-hull, or triple-hull, battleships or similar vessels, which, during a battle or at any other time, may almost instantly incline downwardly the advancing apron (or the front or rear end of the fin) and entirely submerge the hulls, or partially submerge the same, thus leaving none of the hulls exposed to the enemy's gun-fire or torpedo or bomb attack; while in case a shell or torpedo should pierce or destroy any one of the hulls the apron or front end of the fin could be inclined upwardly, which would almost instantly raise the vessel in the water and prevent the damaged hull from being filled with water through the hole made by the shot or other blast, and the vessel would be enabled to continue in service, or, if preferred, escape to a safe place, for repairs; but which would not be possible with war-vessels heretofore known to me, and which latter would, when disabled as described, sink in a very short time and be a total loss.

A further object of my invention is to provide an improved submarine vessel with a plurality of hulls abreast (or nearly abreast), and connected by a fin or fins, whereby the movable fins or aprons may be quickly manipulated and the vessel submerged almost instantly, and be kept under water with little resistance; and yet be unsinkable unless all of its hulls are broken or destroyed.

A further object is to provide plural-hull launches and rowboats, the hulls of which are connected by a fin or fins provided with movable portions, for increasing the safety, speed and capacity of such vessels; whereby such boats would travel with less resistance

when raised partially out of the water, and at the same time be faster than most present day ships if provided with a sufficiently powerful engine.

5 A still further object is to provide toy-boats with a plurality of hulls connected by a fin or fins, as described, as such toys would be both useful and instructive.

In the drawings,

10 Figure 1 is a top plan-view of a triple-hull vessel, constructed in accordance with my invention.

Fig. 2 is a transverse section of the same, taken on the line 2—2 of Fig. 1.

15 Fig. 3 is a vertical section of a portion of the central (or main) hull, the section being taken on the line 3—3 of Fig. 1, and

20 Fig. 4 is a detail perspective view of the apron, or rudder, at one end of the fin to which it is hinged.

In the present illustration of my invention I have shown a "triple"-hull vessel, there being a larger, or main, hull 1, with a smaller hull 2 located on opposite sides of said main hull; thus providing three hulls; but I distinctly state that I do not limit my claims to the "triple"-hull vessel, as it is obvious that the number of hulls may be diminished to two, or increased above three, 25 as desired, the present illustration being illustrative of the principle of my invention, which is that of a vessel having a "plurality" of hulls connected by fins or aprons located in the space between said hulls, below the 30 water-line of the latter.

The several hulls 1 and 2 may be made of either wood or metal, or partly of wood and partly of metal, and they, of course, are provided with the usual ribs 3 to which the 40 shell or exterior 4 of the hulls is attached, the said shell in the present instance being shown of sheet-metal.

The said hulls 1 and 2 are securely, and permanently, fastened together by means of 45 suitable cross-beams 5 and angular braces 6, which (in the present instance) are all located in the same horizontal plane, and are secured to adjacent beams and braces by common connecting-castings or forgings 7, 50 the said cross-beams extending parallel to each other completely across all of the hulls, spacing them apart, and holding said hulls parallel to each other.

The fins are designated by the numeral 8, 55 and in the present instance, they are made of sheet-metal plates stiffened at their edges and along the center of their length by means of common angle-bars 9 which are secured to said sheets by means of rivets, the 60 angle-bars at the marginal-edges of said fins being riveted or otherwise secured to the adjacent sides of the hulls throughout the length of said fins, except the movable parts thereof.

65 The movable parts of said fins are, in the

present illustration, in the form of aprons or diving and elevating Rudders 10, made of sheet-metal stiffened by angle-bars 9, in the manner previously described in connection with said fins, and having their edges which are adjacent the ends of said fins pivotally or hingedly attached to said fin ends by means of common hinges 11, which are secured to said fins by means of rivets or other proper fastening-means, and through the 70 eye of which hinges loosely turns or rocks a horizontal apron-shaft 12 fixed to the edges of said aprons by integral eyes 13 formed on said aprons and through which said shaft passes and in which said shaft 75 is fixed by means of pins 14 passed through both shaft and said eyes 13; whereby, when said shaft is rocked the free edge of said aprons will be correspondingly raised or lowered in the water. (See Fig. 4). 80

85 The said fins 8 are preferably made strong, as shown, to assist in fastening together the adjacent hulls 1 and 2 at a point some distance below the water-line, so that said hulls will be secured above the water-line by the 90 said cross-beams 5 and braces 6, and below the water-line by the said fins, thus making a very durable and strong construction, which securely binds all of said hulls together at said points, and makes them practically a single hull.

The said fins 8 are made of sufficient size, and of such shape in plan-view, as to fill the space between the hulls 1 and 2 for a distance approximating one-half the length of 100 the shorter hulls.

It will, of course, be understood that all of the hulls may be of the same length and capacity, although I have herein shown a central hull of greater length and capacity 105 than that of the two side hulls.

It will also be understood that any common means may be used for raising and lowering the said aprons 10, and in the present illustration I have shown a rock-lever 15 110 fixed upon the said apron-shaft 13 and having rods 16 pivotally connected to its opposite ends, to be extended to any desired location aboard ship that is convenient for the operator; there to be moved by hand, or 115 mechanically, to raise or lower said aprons.

In the present case, the apron-shafts 12 are passed through the sides of the hull 1, common stuffing-boxes 17 being used to prevent leakage of water into the said hull 120 past said rods, and the said rock-levers 15 are located in said hull, the said rods 16 being extended toward the center of said hull and there connected pivotally to other rock-levers 18 fixed on rock-shafts 19 carrying gear-wheels 20, which latter may mesh with a gear 21 of the ship steering-gear, or of a special power-driven gear of any common construction; whereby both of the said gear-wheels 20 will be simultaneously moved 130

in the same direction, to elevate the apron 10 at one end of the fins 8 and simultaneously lower or depress the apron at the opposite end of said fins. Or, if desired, the aprons 5 at the front and rear ends of said fins may be moved separately, or independently, as the judgment of the shipbuilder may dictate.

The operation of my invention will be apparent from the above description.

10 I claim the following as my invention:

1. A ship or boat having a plurality of hulls placed side by side and spaced apart by means which securely bind said hulls to each other, and an apron located in the space 15 between said hulls, and acting as a binding means for the same at a point below the water-line thereof; said apron having a movable portion which when depressed will cause the hulls to submerge, and which when 20 elevated will cause the hulls to rise.

2. A ship or boat having triple hulls placed side by side; cross-bars and braces which space apart and securely bind said hulls to each other at a point above the water- 25 line thereof; a fin extending horizontally across the space between adjacent ones of said hulls, to bind same together at a point below the water line; and an apron hinged at the end of said fin, for the purposes de- 30 scribed.

3. A ship or boat having a plurality of hulls spaced apart but connected securely; a fin extending horizontally in the space be-

tween said hulls below the water line there- 35 of; and aprons hinged at both ends of said fin, for the purposes described.

4. A ship or boat having a plurality of hulls spaced apart but connected securely; a fin having its marginal edges fixed to the adjacent sides of two of said hulls in the 40 space between the latter at a point below the water line; an apron hinged at the end of said fin; and suitable means for moving said hinged apron up and down, for the purposes 45 described.

5. A ship or boat comprising a plurality of connected hulls having a space between them, and a long horizontal fin fixed in the space between said hulls, and extending approxi- 50 mately one-half the length of said hulls, below the water-line.

6. A ship or boat comprising a plurality of connected hulls having a space between them; a long horizontal fin fixed in the space 55 between said hulls, and extending approxi- mately one-half the length of said hulls below the water-line; and aprons hinged to said fins.

In testimony whereof, I have signed my name to this specification, in presence of two 60 subscribing witnesses.

RICHARD E. HORNBECK.
